UNITED STATES PATENT OFFICE.

ERIK J. MORDT, OF EVANSTON, ILLINOIS.

DESIGN FOR A JUMPING ROPE.

Application filed October 8, 1926. Serial No. 19,279. Term of patent 3½ years.

To all whom it may concern:

Be it known that I, ERIK J. MORDT, a citizen of the United States, residing in Evanston, in the county of Cook and State of Illinois, have invented a new, original, and ornamental Design for Jumping Ropes, of which the following is a specification, reference being had to the accompanying drawing, forming part thereof.

As shown in these drawings;

Figure 1 is a side view of a jumping rope showing my new design; and

Figure 2 is an end view of the handle portions.

I claim:

The ornamental design for a jumping rope as shown.

ERIK J. MORDT.
